Primary Examiner — Llorellys Martinez(74) *Attorney, Agent, or Firm* — Oppedahl Patent Law Firm LLC(57) **CLAIM**

The ornamental design for a combined bracelet and clasp, as shown and described.

DESCRIPTION

FIG. 1 is a front perspective view of a combined bracelet and clasp showing our new design.

FIG. 2 is a back perspective view of FIG. 1;

FIG. 3 is a front view of FIG. 1;

FIG. 4 is a back view of FIG. 1;

FIG. 5 is a left side view of FIG. 1;

FIG. 6 is a right side view of FIG. 1;

FIG. 7 is a top view of FIG. 1; and,

FIG. 8 is a bottom view of FIG. 1.

The broken lines in the drawings represent portions of the combined bracelet and clasp that form no part of the claimed design.

1 Claim, 8 Drawing Sheets(56)
